UNITED STATES PATENT OFFICE.

ELIJAH B. CORNELL, OF PHILADELPHIA, PENNSYLVANIA, ASSIGNOR TO THE
NATURAL GAS FUEL COMPANY, OF SAME PLACE.

HEATING IN FURNACES.

SPECIFICATION forming part of Letters Patent No. 434,380, dated August 12, 1890.

Application filed December 10, 1889. Serial No. 333,192. (No model.)

To all whom it may concern:

Be it known that I, ELIJAH B. CORNELL, a citizen of the United States, residing at Philadelphia, in the county of Philadelphia and State of Pennsylvania, have made a new and useful invention in Methods of Heating in Furnaces, of which the following is a specification.

My invention relates particularly to improvements in that branch of the art in which heat is generated through the agency of injected steam.

Heretofore it has been customary to inject steam into, through, or upon an incandescent mass of carbonaceous fuel, and by the decomposition of such steam through the affinity of its oxygen for the carbon of the fuel to obtain hydrogen gas, which, by admixture of atmospheric air, is enabled to be burned. My object is to cause the decomposition of steam into its constituent gases, hydrogen and oxygen, without loss of the oxygen through affinity for carbon, and to obtain thereby an oxyhydrogen gaseous mixture constituted in chemically-combining proportions, instead of merely or chiefly hydrogen, for use in producing heat.

In my endeavors to obtain this result I have discovered that I obtain the oxyhydrogen gaseous mixture in greatest amount by causing steam (not necessarily superheated) to impinge upon a neutral flame. By a "neutral flame" I mean a sufficient amount of burning gas or gases that will have no chemical affinity for either of the constituents of the steam, and the sufficiency I consider satisfied when this burning gas is capable of decomposing the steam by single thermochemical action. I term such decomposition "thermolysis," and I consider the thermolyzed steam to result in an oxyhydrogen gaseous mixture identical with that obtained by me in thermolyzing in a retort, as described in an application made by me for Letters Patent bearing the Serial No. 326,476, and filed October 9, 1889.

I have also found that such a neutral flame is best provided by the method described in the aforesaid application. I have also discovered that the oxyhydrogen gaseous mixture obtained by the impinging of steam upon and into a neutral flame does not by itself readily ignite, and I find requisite to cause

ignition and combustion of this oxyhydrogen gaseous mixture in practicable amount a certain proportionate admixture of a similar gaseous mixture that has been acted upon catalytically by passage through a catalytic material, as described in the aforesaid application. Under this condition of admixture I find that the oxyhydrogen gaseous mixture obtained from thermolysis in a neutral flame, as described, is readily ignitable; but I find that a "milder" and better distributed combustion is obtained by causing the steam in its injection to introduce a volume of air.

To carry my invention into effect, I set in the front wall of the furnace any ordinary or desired form of steam-injector, and I arrange this injector in such a position as will cause the steam to impinge on the hottest part of the neutral flame arising from the grate of said previously-described apparatus and allow of least resistance in carrying forward the volume of gaseous mixture produced, which gaseous mixture subsequently burns in the heating-chambers and flues of the furnace.

The accompanying drawing illustrates the arrangement of parts of this my invention, I being the injector set in the front wall F and connected by the pipe P to a boiler at such point as will provide so-called "dry" steam.

The accompanying drawing is also illustrative of a form of furnace equipped with devices for practicing my invention in its entirety, a steam-boiler not being shown, so as to indicate the fact that it may be located at a distance from the furnace.

A is the furnace, composed of fire-box B, having grate-bars b, ash pit or chamber below said grate-bars, in which is located a pipe or injector C, having connection C' with a retort D, located within the fire-box, preferably in such position that it is subject to the heat thereof, which, while it is hot enough to cause it to convert steam into its constituent gases by thermolysis in the retort, is not sufficient to fuse or otherwise deteriorate the retort.

On the grate-bars is placed any suitable catalytic material forming what I have termed a "septum," for acting on the constituent gases of the decomposed steam as they pass through the same. In practice for steam-boiler furnaces I use the fuel or coal as a cata-

lytic material or septum, as it subserves the purpose of initially generating the steam and initially inflaming the gases and maintaining constant inflammation.

5. The practice of my improved method with the above-described apparatus is as follows: The catalytic material on the grate-bars is first ignited or heated to initially generate steam and heat the retort D, if the boiler is 10 adjacent thereto, or to heat the retort D if the steam-supply is brought from a distant location. The dry steam entering the retort D is by thermolysis decomposed in this retort into its constituent gases, which pass through the 15 injector C or continuation of the pipe C' and enter the ash-pit or chamber below the grate-bars b. The gases as they pass through the catalytic material are acted upon, and are subsequently burned, partly in and immediately 20 above the catalytic material and partly in the further flues and chambers of the furnace, as admixed with the oxyhydrogen gaseous mixture obtained from the steam injected through the injector I in the front wall of the furnace 25 and thermolized by the heat of the neutral flame.

Having thus described my invention, what I claim, and desire to secure by Letters Patent, is—

30. 1. The method of heating in furnaces which consists in forming an oxyhydrogen gaseous mixture by thermolysis of steam in a neutral

flame, causing admixture therewith of a catalytically-treated gas or gaseous mixture and burning the same, substantially as described. 35

2. The method of heating in furnaces which consists in forming an oxyhydrogen gaseous mixture by thermolysis of steam in a neutral flame in connection with injected air, causing admixture therewith of a catalytically-treated 40 gas or gaseous mixture, and burning the same, substantially as described. 45

3. The method of heating in furnaces which consists in thermolizing steam into its constituent gases and subjecting these gases to 50 catalytic action, thermolizing steam into its constituent gases in a neutral flame, causing admixture of the former with the latter gases, and burning the same, substantially as described.

4. The method of heating in furnaces which consists in thermolizing steam into its constituent gases and subjecting these gases to catalytic action, thermolizing steam into its constituent gases in a neutral flame in connection with injected air, causing admixture of the former with the latter gases, and burning the same, substantially as described. 55

In testimony whereof I affix my signature in presence of two witnesses.

ELIJAH B. CORNELL.
